UNITED STATES PATENT OFFICE.

WILLIAM T. SMITH AND WILLIAM K. SMITH, OF PHILADELPHIA,
PENNSYLVANIA.

DESIGN FOR WOVEN FABRIC.

SPECIFICATION forming part of Design No. 23,988, dated February 5, 1895.

Application filed October 20, 1894. Serial No. 526,514. Term of patent 7 years.

To all whom it may concern:

Be it known that we, WILLIAM T. SMITH and WILLIAM K. SMITH, residing at Philadelphia, in the county of Philadelphia and State of Pennsylvania, have invented and produced a new and original Design for a Woven Fabric, of which the following is a specification, reference being had to the accompanying drawing.

The leading feature of our design is the representation of a leopard skin, shown on a contrasting ground, said skin surrounded by a scalloped border as shown in the accompany-

ing drawing; which is sufficient to enable others skilled in the art, to make and use our invention.

Having as above fully described our invention, what we claim as new, and desire to secure by Letters Patent, is—

The design for a woven fabric, as shown in the accompanying drawing.

W. T. SMITH.
